LUTHER W. HARWOOD AND CHARLES D. NEWTON, OF TROY, NEW YORK, ASSIGNEES
TO ELIHU HOSFORD, OF CHICAGO, ILLINOIS.

Letters Patent No. 86,069, dated January 19, 1869.

PLATE OR GRATE FOR BASE-BURNING STOVES.

The Schedule referred to in these Letters Patent and making part of the same.

To all whom it may concern:

Be it known that we, LUTHER W. HARWOOD and CHARLES D. NEWTON, of Troy, in the county of Rensselaer, and in the State of New York, have invented an Improvement in Grates for Base-Burning Stoves; and do hereby declare that the following is a full, clear, and exact description thereof, reference being had to the accompanying drawing, making a part of this specification, in which a vertical central section of our improved grate is shown.

Our invention relates to stoves having a downward draught, and is an improvement upon the grate invented by Elihu Hosford, and secured to him by Letters Patent No. 80,484; and

It consists in the means employed for conducting the current of cold air to the under side of said grate, and compelling it to pass beneath, and cool its entire surface; after which, said air is permitted to escape, and mingle with the downward current of gas from the fuel-chamber, and assist in the process of combustion.

In the annexed drawing—

A represents the grate, consisting of a circular plate or disk of metal, made convex upon its upper side, and resting, by means of lugs, upon another plate or disk, B, corresponding in shape and size with said grate.

The lugs *a a* are reduced in thickness, for about one-half inch from their lower ends, forming a shoulder upon opposite sides, and slots are provided in the disk B, into which the thin ends of said lugs are inserted, the shoulders resting upon the disk, so as to hold said grate and disk apart, and leave a space for the passage of the air.

Upon the lower side of the disk B is a hub, *b*, in which is provided a recess for the reception of the end of a hollow column, C, supporting said disk and grate.

Through the centre of the disk is an opening, corresponding in size to the interior of the column C, forming, in combination with said column, a flue, through which a current of cold air can freely pass upward, beneath the grate.

It will be readily seen that, by the addition of the disk B, the cold air is compelled to pass beneath, and cool the entire grate before being liberated, and that, after having performed such office, said air is brought in contact with the descending column of heated gas from the fuel, at the instant that said gas leaves the fuel-chamber, by which means a more thorough union of the gas and air takes place than could otherwise be effected, and more perfect combustion is insured.

Having thus fully set forth the nature and merits of our invention,

What we claim as new, and desire to secure by Letters Patent, is—

The disk B, or its equivalent, arranged immediately beneath and supporting the fuel-supporting plate A, for the purpose of compelling the current of air entering through the flue C to pass beneath and cool the entire fuel-supporting plate, substantially as herein shown and described.

In testimony that we claim the foregoing, we have hereunto set our hands, this 2d day of January, 1869.

LUTHER W. HARWOOD.

Witnesses: CHARLES D. NEWTON.
